PISTON STRUCTURE

Harry S. Frank, New York, N. Y.

Application July 3, 1933, Serial No. 678,801

5 Claims. (Cl. 309—14)

This invention relates to pistons in general, and particularly to a piston structure composed of two distinct parts made of metals having different coefficients of expansion, such as described in my previous application for Letters Patent, Serial No. 638,686, filed October 20, 1933, of which the present case is, in part, a division.

Pistons made of two metal parts are well known in the art. Yet, up to the present time, it was found rather difficult to keep the two parts permanently united so as to maintain them in perfect alignment under all practical conditions, while they are exposed to the ever changing temperature variation. Many constructions soon develop faults, resulting in scoring of cylinders, while other designs break apart after only comparatively short periods of usefulness. Practically all of the troubles encountered with bi-metallic pistons may be traced to the inefficient connections provided between the head and sleeve, in that they do not allow for a necessary "give" of the less readily expanding piston part, the sleeve.

In the present case, the head portion of the piston is made of the usual design, but the connecting end of the sleeve, which is cast into the head, is specially constructed so as to not only assure a firm, permanent hold between head and sleeve, but at the same time, to facilitate an unrestricted expansion of the head and of the connecting portion of the sleeve, without straining the latter in the least. Such connection may be best compared with an annular hinge construction or an iris diaphragm which automatically opens with the expansion of the head material and closes when the latter contracts.

The object of the present case, therefore, is to provide a multiple part piston, consisting of a head and a sleeve member, in which the connection between the two members is so designed as to prevent them from coming apart, while at the same time permitting them to unrestrictedly expand or contract when subjected to variations of temperature.

The foregoing and other objects of this invention will be more fully apparent from the following description and the accompanying drawing, forming part of my disclosure, which drawing, however, is not intended to limit me to the actual designs illustrated, and in which

Figure 1 represents a cross-section through a portion of the connection between the head and the sleeve of a piston.

Figure 2 is an elevation, partially in cross-

section of the upper or connecting end of a sleeve before having received its final form.

Figure 3 is a similar elevation of the sleeve with the connecting end in its final shape.

Figure 4 is a cross section through a part of a modified form of a head and sleeve connection.

Figure 5 is an elevation of a part of a sleeve with a modified form of a connecting end.

Figure 6 is a top view thereof.

Figure 7 is a cross-sectional view similar to 10 that shown in Fig. 4, with the sleeve connection partially in elevation, and

Figures 8 to 12 illustrate still other modified forms of my head and sleeve connection.

Referring now to Figures 1 to 3, numeral 10 denotes the head of a piston, made of cast metal, preferably aluminum or a composition thereof, which possesses a higher coefficient of expansion than steel or cast iron. Numeral 11 indicates a steel sleeve, the upper end of which is specially prepared to serve as connecting portion and is cast into the head material. This end portion of the sleeve, which is originally cylindrical (as seen in Fig. 2), is provided with a plurality of longitudinal through-cuts 12, which are uniformly spaced over the entire circumference of the sleeve. The metal above each cut is recessed as at 13. These recesses are of uniform width and are spaced by prongs or tangs 14, the width of which latter preferably equals that of the recesses. 30

Before casting the connecting end of the sleeve into the head material, the sections 15 of the sleeve, formed by cuts 12 and recesses 13, are bent inwards to form a frustum of a cone, as illustrated in Fig. 3. It will be observed that through this cone formation of the sleeve connecting portion, the upper ends of cuts 12 and of recesses 13 become narrower, thereby producing dove-tailed recesses, which are essential for the purpose for which they are intended. The bending areas 16 of section 15 substantially coincide with the bottom ends 17 of through-cuts 12, as is plainly visible from the cross-sected part of Figs. 1 and 3.

When the sleeve portion is thus prepared, it is cast into the head material so that the dove-tail shaped recesses are completely covered. Due to the comparatively wide spaces provided between tangs 14, the metal will readily fill recesses 13, thereby effecting a perfect union between the two piston parts in that the head material will dove-tail with recesses 13. Through-cuts 12 being very fine, and in addition drawn together at their top ends, will prevent the metal from entering. Consequently, the lower, wide areas of sections 15 55

are left free for any subsequent movement induced by the expansion or contraction of the head material. Such movement is facilitated through bending areas 16 which serve as fulcrums or 5 hinges for sections 15.

The head material having a higher coefficient of expansion than the sleeve will, when subjected to heat, expand more rapidly than the latter. Since the head material is in interlocking engagement with recesses 13 and tangs 14, it will force 10 sections 15 radially outwards, which movement is aided both by the resiliency of the sleeve material and the so-to-speak pivotal bending zones 16, provided for each section. During contraction of the head material sections 15 are caused to move inwards.

In order to obviate any misunderstanding as to the movements of sections 15, it is to be noted that such movements are in reality infinitesimal. 20 This is particularly due to the fact that during the casting operation the heat of the molten head metal causes an appreciable expansion and an outward movement of sections 15. As the head metal solidifies in cooling, it shrinks and carries 25 with it sections 15, drawing them inwards and bringing them under a slight tension, which facts become beneficial during the practical employment of the piston, when the latter is subjected to quite a lesser heat than that employed in casting 30 the head material. The subsequent expansions of the head in an engine cylinder will, therefore, cause only relatively slight outward movements of sections 15, without subjecting them to undue strains and stresses which might 35 cause breakage at the hinge or bending areas 16. Similarly, when the head material contracts, sections 15 are brought back to their original position which they assume after the casting and cooling operations.

40 In Figures 1 to 3 I have illustrated one of the many possible forms given to the connecting end of the sleeve. In Figures 4 and 7 a modified construction is shown, in which sleeve 18 is rolled at its upper or engaging end to form annular 45 grooves 19 and 20. The rolled portion is slotted at 21 and is provided with either spaced recesses similar to those explained in connection with Figures 2 and 3, or the connecting end is sectioned off in the manner shown in Figures 5 and 50 6, where through-cuts 22 are illustrated, which terminate in V-shaped continuations 23, separating the attaching end of the sleeve into individual sections 24. The upper ends 25 of these sections are fully embedded in the piston head 55 material 26, while their next lower portions 27 are embedded only up to their outer surfaces. The lowermost ends of the sections are free to move about annular bending line 28, when either expanded or contracted by the variations of the 60 volume of the head material. In all other respects, the arrangement of this modification is the same as described in connection with Figures 1 to 3.

In Figures 8 to 12 are illustrated still other 65 possible constructions of flexibly connecting the head and sleeve members of a two-piece piston, by dividing or slotting the conically or otherwise inwardly directed attaching end of the sleeve into sections, the upper parts of which are alternately bent inwards and outwards. In Figures 8 and 9 the upper end of sleeve member 20 is evenly slotted at 30 and formed into a cone. About midway between the bases of the slots and the ends of the tangs 31, produced by the slotting 70 operation, these tangs are alternately bent out-

wards, as at 32, and left projecting inwards, as shown at 33. By this arrangement the portions of the tangs above their middle form an anchorage for the sleeve within the head material, while their portions which are not absorbed by the 5 casting are free to flex about bending line 34.

Figures 10 and 11 illustrate a similar arrangement to that explained above, with the exception that sleeve 35 is bent in sharply at 36, and prongs 37 extend straight upwards until their upper ends 10 are bent alternately in outward and inward directions. These bent ends of the prongs are embedded in the casting of head 38. Figure 12 denotes a modified form of either of the constructions illustrated in Figures 9 and 11, in that 15 prongs 39 are separated more generously at their tops by recesses 40.

All of the above described constructions have for their purpose to enable the connecting end of the sleeve or skirt to readily flex and to adjust 20 itself to the dimensional changes of the head, which changes are caused by the expansion and contraction of the head material, due to changes in temperature, without unduly straining the sleeve material and without loosening the firm 25 connection between the head and the skirt. This is made possible through the particular crown-resembling constructions of tangs, which are all separated from one another and are capable of 30 individually moving about their respective bending areas, which latter functions in the manner of hinges or fulcrums. The dove-tail anchorage between the prongs and the head material provides a firm union between the two members, irrespective of their unequal expansion, due to the 35 different coefficients of expansion the materials of the members may possess. Thus when the head (subjected to far greater heat than the skirt and having a higher coefficient of expansion) gains in its dimension, the resilient individual 40 prongs of the crown will move outwards, independently of any possible expansion of the sleeve material, due to the influence of heat reaching it.

While I have illustrated a few modifications, it is quite selfevident that my invention may assume still other forms, as long as a truly flexible connection between head and sleeve is produced. Consequently, I herewith reserve for myself the right to make changes and improvements in the construction of the piston, as may become 45 ad- 50 visable or necessary in the course of producing it efficiently on a large scale or otherwise, with the understanding that such innovations remain within the broad scope of my idea as covered by the annexed claims. 55

I claim:

1. A multiple-piece piston structure, comprising head and sleeve members, the latter cast into the head material and provided with a connecting end, consisting of a plurality of uniformly 60 arranged prongs, finely spaced from one another at their lower ends, their upper ends, separated by much larger spaces, being imbedded in the head material, which latter fills these larger spaces, whereas the finely spaced lower ends of 65 the prongs are entirely free of the head material, said prongs thus being capable of individually adjusting themselves to any movement induced by the expansion or contraction of the head material, without loosening their firm hold within 70 the latter.

2. In a multiple-piece piston, the combination with a piston head, of a piston sleeve firmly connected therewith, the connecting end of the piston provided with means for rendering the con- 75

nection between the head and sleeve resilient and capable of expansion or contraction, induced by dimensional changes of the head material, said means consisting of a plurality of peripherally 5 arranged prongs, separated at their bottoms by fine spaces, which are entirely free of the head material, and by larger spaces at their tops, which are entirely filled by the head material.

3. In a two-piece piston, the combination with 10 a piston head, of a piston sleeve firmly but resiliently connected at one of its ends with said head, the connection between the two parts adapted to allow for dimensional changes of said head (due to temperature fluctuations) relative to said 15 sleeve, without affecting the firmness of the connection with said head, said connection consisting of an annular arrangement of uniformly spaced prongs, arranged in off-set relation to the body of the sleeve, and separated at their lower 20 ends by fine spaces which are free of the head material, their upper ends being separated by relatively large spaces which are entirely filled by the head material.

4. A two-piece piston, comprising a head and 25 a sleeve, the latter cast at one of its ends into the head material, the cast-in sleeve-end provided with means for interlocking with the head material and for allowing the latter to change its dimensions without affecting its firm connection with said sleeve, said interlocking means 30

consisting of an annularly arranged set of prongs, disposed angularly relative to the body of the sleeve and separated at their lower ends by fine spaces, free of the head material, and at their upper ends by substantially larger spaces, said 5 upper ends being imbedded, whereby the larger spaces, separating these upper ends, are completely filled with the head material.

5. A two-piece piston, comprising a head and a sleeve member, each made of different materials 10 having varying coefficients of expansion, each member adapted to be subjected to different heat-intensities, one end of the sleeve held in firm connection with the head material, and so constructed as to facilitate the expansion of the 15 sleeve connecting portion together with the head, without causing undue stresses in said sleeve material when the head is subjected to heat, such expansion of the connecting portion of the sleeve being independent of the expansion (due to heat) 20 of the sleeve material, the sleeve end connected with the head material consisting of a conical arrangement of uniformly spaced prongs, the lower ends of the prongs being separated by narrow cuts, the upper prong ends being spaced by 25 large, substantially dove-tailed cuts, said upper prong ends being completely imbedded in the head material, so that the latter entirely fills the large cuts, while leaving free the narrow cuts.
